REPEATER

Application filed March 7, 1928. Serial No. 259,823.

This invention relates to automatic repeaters, and more particularly to the non-interfering variety of multi-originating circuit type of automatic repeaters used in connection with municipal fire alarm telegraph systems for acting in response to the formulation of signaling impulses in any one of a plurality of originating or so-called "box circuits" to cause the formulation of corresponding signaling impulses, usually, in one or more so-called "local circuits", and, in what is usually referred to as the reflex type of repeaters, in all other associated box circuits.

Repeating repeaters of the general type to which this invention is particularly suited have been in use for many years, in connection with municipal fire alarm systems, and have long been so built that, after having acted in response to a signaling impulse of any box circuit, they are rendered unresponsive to the subsequent formulation of signaling impulses in other box circuits, which characteristic is termed "non-interference".

In the course of such use, it has been found, as pointed out in greater detail in Patent No. 810,912, dated January 30, 1906, to Frederick W. Cole, that the mere degree of non-interference just referred to proves inadequate when the formulation of signals in two or more box circuits is initiated at or about the same time; so that other characteristics were added to repeaters of the general type referred to such, for example, as those disclosed by said Cole patent, whereby one or another of a plurality of box circuits simultaneously acting at the initiation of their respective signals would be automatically selected, by the action of the repeater, to finally control its action, and so that signaling impulses corresponding to those of the circuit thus ultimately securing exclusive control of the repeater would be formulated in all box circuits which remained inactive at the initiation of the formulation of the signal of such controlling circuit. Such characteristic of these repeaters is usually referred to as "perfect non-interference".

There is, however, a problem relative to the inter-relationship of diverse fire alarm box signals which is usually characterized in this

art by the term "succession". In the case of fire alarm boxes of modern type, (as exemplified by type of fire alarm box indicated in patent to F. W. Cole, No. 1,244,587 of Oct. 30th, 1917) the attainment of so-called "non-interference" and "perfect non-interference" functions, as between boxes in any one circuit, is supplemented by such a so-called "succession" function, so that the running of the mechanism of any fire alarm box is extended, beyond the usual time, in the event that, after the box is started, it relinquishes control of its circuit either because signaling impulses from a previously initiated signal were in course of transmission over such circuit or because the automatic selection well understood by those skilled in this art gave control of the circuit to the simultaneously initiated signal of some other box; to the end that when boxes have thus relinquished control of their circuit, they may later reassert such control and effect the formulation of their signals in an orderly succession.

Although certain prior art repeaters have acted, as already referred to, so that the signal of a box circuit then in control would be formulated in box circuits which were inactive at the time of the initiation of such controlling signal, the type of such repeaters in general use has not so acted, when the formulation of signaling impulses are initiated in one or more circuits at or about the same time, as to cause delay in formulation of signals of boxes in circuits which are non-controlling, in the sense that the repeater has temporarily rejected their control in favor of the circuit automatically selected to control the repeater for the time being. As a result, fire alarm boxes in such non-controlling circuits, even though of the most improved non-interference and succession type, would proceed with the formulation of their respective signals in such circuits; and, at the conclusion thereof, would come to rest, instead of bringing into action the successive feature so as to extend operation and effect signal formulation at a time when the repeater was free to respond thereto following the completion of the signal of the box first in control.

In other words, such prior art repeaters

have failed to so govern the box circuits associated therewith as to render as effective the so-called perfect non-interference and succession features of fire alarm boxes acting 5 to simultaneously initiate signals in diverse box circuits as if such boxes were included in the same box circuit.

It is, therefore, an object of this invention to provide an automatic repeater, of the general character referred to, in which the succession functions of fire alarm boxes connected in different box circuits associated therewith, will be as fully accomplished as if such boxes were in the same circuit.

15 A further object of this invention is to provide means suited for application to fire alarm automatic repeaters such as are now in common use, whereby they will act to effectuate such perfect non-interference and succession functional relationships between boxes connected in diverse box circuits.

20 A further object of this invention is to provide means suited for application to automatic fire alarm repeaters such as were in common use previous to and at the time of the introduction of the improvement of the Cole patent referred to, whereby such repeaters may be caused to effectuate both the perfect non-interference and the succession functions 25 of boxes connected in diverse circuits associated therewith without occasion for the utilization of the invention of said Cole patent.

30 A still further object of this invention is to provide instrumentalities suited for comparatively inexpensive manufacture and capable of being readily applied to any of the types of prior art repeaters which are now in more or less common use.

40 Other and more specific objects and advantages will appear in the following description or will be apparent to those skilled in this art.

45 In constructing this invention, means are provided whereby the repeater, in responding to activity of any group of box circuits, acts to render itself unresponsive to all other box circuits, such action will also coordinate the activities of all circuits remaining in 50 controlling relationship with the repeater,—to the end that the inter-relationship between the boxes in the circuits whose activities are so coordinated will be substantially that which would exist were all such boxes normally included in one circuit.

55 In order that the details of this invention may be better understood, an illustrative embodiment thereof is shown in the accompanying drawings in which—

Figure 1 is an elevation of a portion of the mechanism of a repeater embodying this invention, comprising the magnet of a box circuit, its armature and the mechanism individually associated therewith;

Figs. 2 and 3 show certain of the parts of Fig. 1 in certain abnormal positions; and

Fig. 4 is a schematic representation of the electrical connections of three typical signaling circuits with the significant parts of an automatic repeater embodying this invention.

With a view of facilitating the comprehension of this invention, I have illustrated same as applied to mechanism of a repeater such as indicated in Figs. 1, 3, 4 and 5 of Patent No. 810,912, hereinbefore referred to, although this invention is adapted for corresponding application to other types of repeaters. It is to be observed, however, that the mechanism shown in the accompanying drawings and hereinafter described in detail does not include the levers 45, and associated parts, which are of the essence of the invention disclosed by said patent, as the use thereof is not required in connection with the invention hereinafter disclosed, although such parts need not be removed from an existing repeater when it is rebuilt to conform with this invention, as the presence of such parts is unlikely to prove detrimental. Wherever the accompanying drawings illustrate an element which may conveniently be constructed and operated the same as in said Patent No. 810,912, it is here given the reference number or character used therein and reference may be had to that patent for further description of such elements.

Fig. 1 includes parts constituting one of the originating mechanisms of a repeater, such as that of said Cole patent; there being several such mechanisms, one for each of a plurality of normally independent current paths, which paths are suited for inclusion in respective ones of a corresponding plurality of originating or box circuits. Said parts include the electromagnet 1, having the winding 2 (see Fig. 4) for inclusion in a box circuit, and an associated moving device comprising the armature 3 and the armature lever 4 to which the retractile spring 5 is applied.

It will be readily understood by those skilled in this art that the shaft 6 is associated with repeating mechanism and controlling mechanism therefor which is rendered responsive to all of the originating mechanisms and which, at times, reacts upon such mechanisms as hereinafter more fully explained; being controlled by and controlling the rocking of said shaft in accordance with usual practices in municipal fire alarm repeaters of the types in general use in this country. Examples of such mechanism are indicated in the drawings of the Cole patent hereinbefore referred to and in the patent to E. J. Butler, dated January 4th, 1927, No. 1,613,018. In said Cole patent, the details of such mechanism are more fully shown in Fig. 1, in which the corresponding shaft is

also indicated by the numeral 6 and is connected with the other parts of the mechanism controlled by and controlling the rocking of said shaft by the parts 8 and 9. In said Butler patent the details of such mechanism are best shown in Fig. 1 in which the corresponding shaft is indicated by the number 72, and the connection between such shaft and other parts of such mechanism is accomplished by the parts 74 and 75. Inasmuch as the details of such well known mechanism form no part of this invention, they are not herein shown or particularly described.

The releasing lever 7 is fixed upon said shaft 6 to rock with same around the axis thereof. The adjusting screw 7' is carried near the free end of the lever 7, for engagement by the armature lever to effect the release of the mechanism just referred to and for the further purpose of effecting restoration of said armature lever 4 in response to rocking of said shaft 6 by such mechanism as may be associated therewith.

Repeating mechanism and controlling mechanism, such as that just referred to as being so associated by the shaft 6 as to be controlled by and to control the rocking of said shaft, ordinarily includes mechanism for formulating signaling impulses in the current paths of each of the originating mechanisms. Such formulating mechanism is diagrammatically indicated in Fig. 4 by fragments of a cylinder 17 carried by a shaft 13 and carrying plates 18, one such plate for each of said originating mechanisms; a pair of brushes 19 being associated with each of such plates 18 so that rotation of said cylinder 17 will effect alternate closing and breaking of an electrical connection between each pair of brushes 19 by alternately bringing respective associated plates 18 into and out of engagement with such pairs of brushes.

The locking shaft 20 corresponds with the rockshaft C of Patent No. 468,473, dated Feb. 9, 1892, to Crane and Cole; which, like the shaft 20 of the Cole patent and the shaft 98 of the Butler patent, hereinbefore referred to, are representative of corresponding shafts in the types of municipal fire alarm repeaters in general use, in which such a shaft is arranged for operation by mechanism which, together with that shaft and the parts operable thereby, constitute lock control mechanism involving retarded operative mechanism so associated with the repeating mechanism and controlling mechanism hereinbefore referred to as to effect certain predetermined action of such shaft at the commencement of each term of the activity of any originating circuit and to effect different predetermined action after the conclusion of each such term of activity; such lock control mechanism usually being so arranged that such last named action will be effected only when the repeating mechanism has remained

inactive for a period longer than the longest interval between responses thereof to any signal. The shaft 20 of Figs. 1, 2 and 3 is arranged to rock in a counter-clockwise direction to an abnormal position at the commencement of such a term of activity and to rock in a clockwise direction to its normal position after the termination of such term of activity; thus resembling the shaft C of the aforesaid Patent No. 468,473. Inasmuch as details of various types of such lock controlling mechanism and retarded operative mechanism, suited for use with this invention, are well known and form no part of this invention, only such parts are here shown as might be considered to form part of this invention or might facilitate a ready comprehension thereof.

Associated with each originating mechanism is an independently movable locking member or pendant 21, which is in the form of a pendant pivoted to the free end of the lever-arm 68 which, in turn, is fixed upon shaft 20. A spring S constantly tends to swing the free end of the pendant toward the lever 4, and said pendant has the lugs or projections 21^a, 21^b, 21^c, formed therein, for purposes which will be hereinafter more fully explained.

The locking lever 31 carries the hook 32 at an end thereof for at times retaining the lever 4 in attracted position; a counter-weight 30 being so mounted on said lever 31 as to tend to swing the hook 32 out of the path of the hook 33 which is formed in the free end of said lever 4. A locking spring 30^a is carried by the lever 31 adjacent said hook 32 for engagement by the projection 21^c of the pendant 21; said parts being so relatively formed and arranged that—when said pendant is in the position which it assumes while the moving device 3, 4, is in attracted position and the shaft 20 is in normal position—the free end of said spring 30^a will be in the path of such movement of said projection as occurs incident to rotation of said shaft 20 from normal to abnormal position; and so that—when said pendant is in the position which it assumes while said moving device is in retracted position, so that the hook 33 is outside of the hook 32 (to the left of hook 32 as viewed in Fig. 1)—the free end of said spring 30^a will not be in the path of such movement of said projection 21^c.

A lever 31^a is fixed upon the shaft 34 so as to act in response to counter-clockwise rocking of said shaft to move the lever 31 in opposition to the influence of the weight 30 so as to carry the hook 32 into the path of the hook 33. Said shaft 34 corresponds with a shaft designated by a like number in the Cole patent, and with the shaft numbered 80 of the Butler patent, hereinbefore referred to; being representative of corresponding

shafts in the types of municipal fire alarm repeaters in general use; and being arranged for operation by or incident to the action of the repeating mechanism and controlling mechanism so that whenever the armature 3 of any originating circuit mechanism has been released by its magnet 1 and thereby permitted its associated lever 4 to respond to its spring 5 to act to so rock the shaft 6 as to release the associated repeating mechanism and controlling mechanism, and said shaft 6 has thereupon been rocked in the opposite direction so as to carry the lever 4 to a position which will permit the hook 33 10 to be locked by the hook 32, the shaft 34 will thereupon be so rocked as to move the hook 32 as just described, and, thereupon, the shaft 6 will cease to act to hold in attracted position the levers 4 associated therewith, and such lever 4 will thereupon move so as to bring its hook 33 into engagement with said hook 32, in response to the pull of the spring 5, unless such lever 4 is prevented from so doing by the attraction of the armature 3 to its associated magnet 1.

From the foregoing it will be apparent that the repeater shown includes means comprising locking mechanism for all originating mechanisms for governing the responsiveness of the repeating mechanism to said originating mechanisms whereby the initiation of activity in a plurality of such originating mechanisms will so abnormally condition the independently movable locking member 21 of originating mechanisms then inactive as to render the repeating mechanism unresponsive only to the circuit mechanisms then inactive; each locking member 21 being so associated with its corresponding originating mechanism as to avoid locking action thereof when the moving device 3, 4, of such originating mechanism is out of its normal position; the locking members 21 of the various originating mechanisms being connected by means of the shaft 20 and the respective arms 68 for response to lock controlling mechanism comprising the shaft 6 controlled by movement of any moving device 3, 4, out of its normal position for simultaneously effecting actuation of the locking members 21 to lock down the locking levers 31 associated with all originating mechanism then in normal position.

A contact lever 38 is mounted adjacent the pendant 21, the free end of said lever being disposed in a relationship to the projection 21^a of said pendant functionally corresponding to the relationship of the locking spring 30^a to the projection 21^c carried by said pendant, as hereinbefore more fully explained; to the end that, when the shaft 20 is rocked in counter-clockwise direction (as is the case at the commencement of each term of signaling activity of the repeater) the originating mechanisms then inactive (i. e. those whose armatures remained in attracted position

during the time that the shaft 6 was in abnormal position) will be prevented from thereafter so rocking the shaft 6 as to functionally affect the repeater; while leaving said shaft 6 (and hence the mechanism responsive to rocking thereof) responsive to the originating mechanism or mechanisms whose armature or armatures were abnormally positioned incident to the first abnormal positioning of the shaft 6 of a series of such abnormal positionings representative of the term of activity of the repeater in the course of its response to any signal; the contact levers 38 of the various originating mechanisms being normally or abnormally positioned accordingly as the levers 31 of such units are free from or held in locking position by engagement of their associated pendant projection 21^c with their locking springs 30^a.

A contact 39 is mounted adjacent to contact lever 38 in such relation thereto as to be engaged thereby except when said contact lever 38 has been abnormally positioned through the engagement of the pendant projection 21^a therewith, as just described in greater detail.

The parts thus far described correspond with such as are found in municipal fire alarm repeaters in general use and such as are indicated by the patents hereinbefore referred to. For reasons well understood by those skilled in this art and which have been more fully pointed out in the Cole and Butler patents hereinbefore referred to, a repeater comprising no more than such structure and inter-relation of parts as hereinbefore described, would be subject to confused actuation (such as would result in the formulation of false or incorrect signals) in the event that boxes associated with two or more of the originating mechanisms thereof were so set in motion as to break their respective circuits at or abut the same time. Furthermore, such a repeater would in no wise assure the functioning of the so-called non-interference and succession mechanism in boxes of such respective circuits so that, not only would the action of the repeater in response to alarms originating in such circuits be so confused, one by the other, that the repetition thereof would be unintelligible, and would fail to cause either box to suspend the transmission of its signal and give the other the right of way; but no matter how highly developed the non-interference and succession mechanisms of such boxes might be for cooperation with like mechanisms of other boxes if connected in the same circuit, the interposition of the automatic repeater between their circuits would prevent such reaction from the signal of one box upon the mechanism of the other box as to assure that a box or boxes whose signals were not being correctly repeated would continue operation until the repeater was free to

correctly handle the signal or signals so affected.

In order, therefore, to assure that the non-interference and succession functions of fire alarm boxes connected in diverse box circuits associated with a repeater constructed as shown by the accompanying drawings, will be as fully accomplished as if all such boxes were connected in one circuit, means is provided which is responsive to all originating mechanisms for coordinating the activities of simultaneously active mechanisms, which means is shown as comprising contacts operable by a member of the locking mechanism to effect functional interconnection between the circuits of simultaneously active originating mechanisms by effecting serial interconnection of such circuits.

The general arrangement of such contacts with relation to each other and to the circuits of a group of three originating mechanisms will be best understood by referring to the diagrammatic representation of Fig. 4; in which it will be noted that each of the originating mechanisms, as here indicated by the letters A, B and C, is equipped with a group of contacts comprising the members *d*, *e*, *f*, *g*, *h*, *i*, the said contact member *d* being situated between the contact members *f* and *h* and said contact member *e* being situated between the contact members *g* and *i*; and said contact members *d* and *e* being biased for movement into engagement with said contact members *f* and *g*, respectively.

35 An insulating tie bar *j* connects the free ends of the contact members *d* and *e*, a portion of said tie bar *j* being so disposed with relation to the projection 21^b formed in the pendant 21 that when the shaft 20 is moved from normal to abnormal position at a time when the associated moving device 3, 4, is so retracted as to carry the projections 21^a and 21^c out of the paths of the contact lever 38 and the locking spring 30^a, respectively, said projections 21^b will engage said bar *j* and move the contact members *d* and *e*, preferably first into engagement with the contact members *h* and *i*, respectively, and thereupon move said contact members *d* and *e* out of engagement with the contact members *f* and *g*, respectively.

The electrical connections shown in Fig. 4 include three normally independent current paths generally designated by the letters A, B and C, representative of three respective box or originating circuits. Circuit A includes a battery *a*¹, from one terminal of which a conductor *a*² connects one of the keybreak contacts of a non-interfering and succession box diagrammatically indicated at *a*³, the other of the contacts of said box being connected to one terminal of the non-interfering magnet of such box and the other terminal of such magnet being connected through the conductor *a*⁷ to the contact mem-

bers *g* and *h* of the originating mechanism associated with circuit A; from the other terminal of the battery *a*¹, conductor *a*⁸ connects with one terminal of the magnet winding 2 of the originating mechanism of circuit A. Batteries *b*¹ and *c*¹ of circuits B and C are correspondingly connected with their associated boxes *b*³ and *c*³ and their respective originating mechanism contacts *g* and *h* and magnet windings 2 through conductors *b*², *b*⁷, and *b*⁸ and *c*², *c*⁷ and *c*⁸, respectively.

The connections between the parts of the originating mechanism of circuit A are as follows: From the remaining terminal of the winding 2 of magnet 1 to one of the brushes 19 and to the contact 39, from the other brush 19 to the contact member *e* and to the contact lever 38, and from the contact member *i* to the contact member *f*. The parts of the originating mechanisms for circuits B and C are similarly connected.

20 The contact member *d* of the originating mechanism of circuit A is connected through conductor *h* to contact members *f* and *i* of the originating mechanism of circuit B, the conductor *h*' correspondingly connecting the contact member *d* of the originating mechanism of circuit B with the contact members *f* and *i* of the originating mechanism of circuit C, and the conductor *h*'' correspondingly connecting contact member *d* of the originating mechanism of circuit C with contact members *f* and *i* of the originating mechanism of circuit A. Obviously, any desired number of originating mechanisms may be correspondingly connected.

25 From the foregoing it will be apparent that the connections just described are such that, under normal conditions, current paths will be effective as follows: as to circuit A, from one terminal of battery *a*¹, through conductor *a*², through keybreak contacts and magnet windings of box *a*³, through conductor *a*⁷ to contact member *g*, thence through contact member *e* to and through contact lever 38 and contact 39, to and through winding 2 and conductor *a*⁸ to other terminal of said battery *a*¹, thus effecting energization of the repeater magnet 1 of the originating mechanism associated with said circuit A and of the non-interference magnet of the box *a*³ therein. Corresponding current paths will be effective for circuits B and C.

30 In addition to and independently of the foregoing current paths there will be a supplemental normally closed current path as follows: from contact member *d* of circuit A, through conductor *h*, to contact member *f* of circuit B, thence to and through contact member *d* of circuit B, to and through conductor *h*', to and through contact members *f* and *d* of circuit C, thence through conductor *h*'' to and through contact member *f* of circuit A to contact member *d* of said circuit.

35 It will be noted that the arrangement of

the circuit controllers comprising the contact members *d*, *e*, *f*, *g*, *h*, and *i*, with relation to the respective originating mechanisms of the various circuits, is such that the contact members of each originating mechanism are operable, by and throughout abnormal positioning of their associated locking member or pendant 21, to effect serial interconnection between the associated box circuit and the supplemental closed current path, during only those terms of the activity of the repeater at the initiation of which the associated moving device 3, 4, is abnormally positioned; thereby establishing a functionally cooperative relationship between said supplemental current path and the current paths of any two or more simultaneously active mechanisms (i. e. originating mechanisms to which the repeating mechanism is then responsive because they are not locked against causing functional response of the repeating mechanism at a time when other originating mechanisms are so locked) by rendering the current path associated with each such mechanism responsive to abnormal conditioning of the current flow through the current paths of other of such active mechanisms by establishing serial interconnection between such current paths.

Assuming now that the lock controlling mechanism for these circuits has been restored since the repeater last acted in response to a signal, the various parts will be normally conditioned, as indicated by Figs. 1 and 4.

If, while the repeater and its associated circuits are normally conditioned, as just described, a signal be initiated in one of the circuits, as by the operation of the code wheel of the box α^3 , the resultant operation of the various parts will be as follows: Upon the first interruption of circuit A, which will occur when the first tooth of the code wheel of box α^3 is withdrawn from the support of the keybreak contacts, the magnet of said box will be deenergized, but its armature will not drop away because it will then be held against so doing by the fallen keybreak, in accordance with the usual construction and arrangement of such boxes. Such break will also cause the deenergization of the magnet 1 of the originating mechanism of circuit A, so that the associated moving device 3, 4, will be swung by its retractile spring 5 so as to rock the shaft 6 and, at the same time, swing the pendant 21 so as to bring the projection 21^b above the bar *j* and to carry the projections 21^a and 21^c out of the paths of the contact lever 38 and the locking spring 30^a, respectively. The counter-clockwise movement of the locking shaft 20, which will result from the rocking of the shaft 6 as just described, will thereupon carry the projections 21^a and 21^c of the pendant 21 past the free ends of the contact lever 38 and locking spring 30^a, re-

spectively, and will cause the projection 21^b to engage the bar *j* and move same downwardly. During the first portion of such movement of the bar *j* the contact members *d* and *e* will be brought into engagement with the contact members *h* and *i*, respectively, and, during the latter portion of such movement of the bar *j*, said members *d* and *e* will be moved out of engagement with the members *f* and *g*. The said parts of the originating mechanism of circuit A will now occupy the positions indicated by Fig. 2.

While the action just described is taking place in the originating mechanism of circuit A, a different action will be taking place in the originating mechanisms of circuits B and C. As hereinbefore explained, the shaft 13 of the repeating mechanism is rotated whenever the shaft 6 has been rocked, as by the retractive movement of a moving device 3, 4, so as to bring the contact plates 18 carried by the cylinder 17 into engagement with the brushes 19 associated with the respective originating mechanisms, such engagement being timed to occur prior to the movement of the locking shaft 20 from normal to abnormal position; hence, shunts will be established around the connection normally effective between the contact lever 38 and the contact 39 of each of the originating mechanisms of circuits B and C, before said shaft 20 moves from normal to abnormal position.

Considering now the action of the locking mechanism of said originating mechanisms of circuits B and C—it will be noted that as the armatures of such circuits were held in attracted position by their respective associated magnets at the time when the locking shaft 20 moved from normal to abnormal position, the resultant actuation of their contact levers 38 and locking springs 30^a will be such as to bring them to the positions indicated by Fig. 3, the projection 21^a of the pendant 21 of each of these locking mechanisms engaging its associated contact lever 38 and moving same away from the contact 39, and the projection 21^c engaging the locking spring 30^a and moving the hook 32 over the hook 33 so as to render the repeater unresponsive to the moving devices of circuits B and C by preventing movement of said devices such as would effect, through the rocking of the shaft 6, functional activity of the repeating mechanism. During the movement of said pendants 21 just described, the projections 21^b thereof will pass to the right of the bar *j* (as viewed in the drawings) thereby leaving the contact members *d*, *e*, *f*, *g*, *h*, *i* of the originating mechanism of circuits B and C in normal condition.

From the foregoing, it will be seen that during the formulation of a signal from the box α^3 of circuit A, under the conditions just described, the current path of said cir-

cuit will include the conductors k , k' and k'' and the contact members d and f of the originating mechanisms of circuits B and C (the normal connection between contact members g and e of the originating mechanism of circuit A being interrupted) and that, otherwise, the operation of the various parts of the repeater will correspond, substantially, with that of well known types of prior art repeaters.

Assuming now that boxes b^3 and c^3 are so operated as to initially break circuits B and C simultaneously. It will be evident from the foregoing description that the originating mechanisms of circuits B and C will simultaneously act in a manner corresponding with that hereinbefore described in greater detail with reference to the originating mechanism of circuit A; so that the parts of the originating mechanisms of said circuits B and C will assume the relative positions shown by Fig. 2, whereupon there will be effected a serial interconnection between originating circuits B and C, due to the abnormal positioning of the contact members d and e of the originating mechanism of said circuits as follows: from one terminal of the battery b^1 , through conductor b^2 , box b^3 (during closures of the keybreak thereof) and through conductor b^7 to contact member h of the originating mechanism of circuit B, thence to and through the associated contact member d , through conductor k' , to and through contact member i of the originating mechanism of circuit C, thence to and through the associated contact member e , contact lever 38 and contact 39, to and through winding 2 of the repeater magnet 1 of circuit C, thence through conductor c^8 , battery c^1 , conductor c^2 , box c^3 (during closures of the keybreak thereof) and conductor c^7 to and through contact members h and d of originating mechanism of circuit C, thence through conductor k'' to and through contact members f and d of the originating mechanism associated with circuit A, thence through conductor k to and through contact members i and e , contact lever 38 and contact 39 of the originating mechanism associated with circuit B, to other winding 2 of the magnet 1 of said originating mechanism, through conductor b^8 to the other terminal of the battery b^1 .

Assuming now that the code signal number of the boxes b^3 and c^3 are 213 and 132, respectively, as shown,—it is evident that when the second tooth of the code wheel of box b^3 unlocks its non-interference armature upon closure of its associated keybreak, the current path through the non-interference magnet of said box will remain open because of the break in series therewith at the keybreak of the box c^3 , so that the non-interference armature of the box b^3 will move to retracted position, leaving box c^3 in complete control of circuits B and C—and hence of the

entire repeater. Such armature retraction will thereafter react upon the succession mechanism of the box in a well known manner so that, after the circuit has been finally closed following the completion of the signal of the box c^3 , the box b^3 will proceed with the formulation of its signal; all non-interfering and succession functions thus being as well accomplished as would have been the case had boxes b^3 and c^3 been included in the same circuit when they were set in motion.

While I have shown serial interconnecting means for establishing a functionally co-operative relationship between originating mechanisms of simultaneously active circuits, it will be apparent to those skilled in the art that corresponding results may be obtained, pursuant to the teachings of this invention, by means other than those herein shown and described in detail. It should also be understood that the specific embodiment of this invention shown by the accompanying drawings and hereinbefore more specifically described is illustrative only, for the purpose of facilitating a comprehension of the nature and objects of this invention and this invention should not be deemed as limited by these details, nor to any of them, except insofar as such limitations are included within the terms of the following claims, in which it is intended to claim all novelty inherent to this invention as broadly as is permissible in view of the prior art.

What is claimed is:

1. In a repeater: a plurality of originating mechanisms each comprising an electromagnet and a moving device controlled thereby; locking mechanism for all originating mechanisms comprising independently movable locking members associated with respective originating mechanisms, each locking member subject to locking activation thereof only when the moving device of its associated originating mechanism is normally positioned, and lock controlling mechanism involving means controlled by movement of any moving device out of its normal position for simultaneously effecting activation of the locking members associated with all originating mechanisms then in normal position;—in combination with independent circuit controllers for the current paths of respective originating magnets, means for abnormally positioning respective circuit controllers only when locking action of the locking member occurs when the associated moving device is abnormally positioned; and conductors so interconnecting said circuit controllers as to effect such functional interconnection between the current paths of all originating magnets whose circuit controllers are abnormally positioned, that an abnormal conditioning of any one of such paths causes an abnormal conditioning in the other of such paths the

same as if such abnormal conditioning originated in such paths.

2. In repeating mechanism for use in an automatic repeater having retarded operative mechanism for lock controlling mechanism to effect restoration, of such locking members as may at any time be abnormally positioned, but only after the lock controlling mechanism has remained inactive for a period longer than the longest interval between responses thereof to any signal: a plurality of originating mechanisms each comprising an electromagnet and a moving device controlled thereby; locking mechanism for all originating mechanisms comprising independently movable locking members associated with respective originating mechanisms, each locking member subject to locking activation thereof only when the moving device of its associated originating mechanism is normally positioned, and lock controlling mechanism involving means controlled by movement of any moving device out of its normal position for simultaneously effecting activation of the locking members associated with all originating mechanisms then in normal position; in combination with circuit controlling mechanism for the current paths of the originating magnets involving means responsive to activation of the locking members to effect such functional interconnection between current paths of originating magnets whose moving devices are simultaneously out of normal position upon occurrence of such activation, that an abnormal conditioning originating in any one of such paths causes a like conditioning of the other of such paths the same as if such abnormal conditioning originated in such paths.
5. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
10. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
15. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
20. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
25. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
30. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
35. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
40. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
45. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
50. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.
55. 3. In a repeater: a plurality of originating mechanisms each comprising an electromagnet and a moving device controlled thereby; locking mechanism for all originating mechanisms comprising independently movable locking members associated with respective originating mechanisms, each locking member subject to locking activation thereof only when the moving device of its associated originating mechanism is normally positioned, and lock controlling mechanism in-
60. A non-interference repeater having individual unit mechanisms for respective response to a plurality of normally independent

volving means controlled by movement of any moving device out of its normal position for simultaneously effecting activation of the locking members associated with all originating mechanisms then in normal position; in combination with circuit controlling mechanism for the current paths of the originating magnets involving means responsive to activation of the locking members to effect such functional interconnection between current paths of originating magnets whose moving devices are simultaneously out of normal position upon occurrence of such activation, that an abnormal conditioning originating in any one of such paths causes a like conditioning of the other of such paths the same as if such abnormal conditioning originated in such paths.

65. 4. A multi-originating circuit fire alarm repeater comprising mechanism arranged responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to serially interconnect with said conductor any circuit active when said mechanism is actuated to effect abnormal conditioning of parts thereof.

70. 5. A multi-originating circuit fire alarm repeater comprising mechanism responsive to activity of any circuit or circuits to be activated for abnormal conditioning of parts thereof at the commencement of any term of such activity and restoration to normal conditioning of such parts after the conclusion of each such term of activity,—in combination with a conductor normally isolated from all originating circuits and means operable by said mechanism to effect serial interconnection throughout each term of the activity of said mechanism between all circuits active when said mechanism is activated to effect abnormal conditioning of parts thereof.

75. 6. A multi-originating circuit fire alarm repeater comprising mechanism responsive to activation of any circuit or circuits to be activated for abnormal conditioning of parts thereof at the commencement of any term of such activity and restoration to normal conditioning of such parts after the conclusion of each such term of activity,—in combination with means operable by the activation of said mechanism to effect such functional interconnection between all originating circuits then active, that abnormal conditioning originating in any one of such circuits will cause like conditioning of the other of such circuits the same as if such abnormal conditioning originated in such circuits.

80. 7. A non-interference repeater having individual unit mechanisms for respective response to a plurality of normally independent

current paths respectively, a current path normally closed and independent of the paths associated with respective mechanisms, and means associated with respective ones of said plurality of normally independent current paths and with said normally closed and independent path, operable responsive to functional activity of the mechanisms associated with respective ones of said normally independent current paths to effect serial interconnection thereof with said normally closed and independent path.

8. In a non-interference repeater for fire alarm circuits having repeating mechanism and controlling mechanism therefor responsive to a plurality of originating circuits, means for governing the responsiveness of said repeating mechanism to said originating circuits whereby the concurrent initiation of activity in a plurality of such circuits will so abnormally condition said means as to render said mechanism unresponsive only to those circuits then inactive,—the combination of means rendered effective by such first named means to serially interconnect, throughout such abnormal conditioning of said first named means, all originating circuits to which said repeating mechanism is then responsive whereby abnormal conditioning originating in any one of such circuits will effect like conditioning of the other of such circuits the same as if such abnormal conditioning originated in such circuits.

9. A non-interference repeater having individual unit mechanisms for respective response to a plurality of normally independent current paths, a supplemental current path and means responsive to said mechanisms for establishing such a functionally cooperative relationship, between said supplemental current path and the current paths of simultaneously active mechanisms, that abnormal conditioning originating in any one of such paths will cause like conditioning of the other of such paths the same as if such abnormal conditioning originated in such paths.

10. A non-interference repeater having individual unit mechanisms for respective response to a plurality of normally independent current paths, and means responsive to said mechanisms for so controlling the current paths respectively associated therewith that simultaneous activity of any two or more said mechanisms will render the current path to which each such mechanism is responsive, so functionally responsive to abnormal conditioning of the current flow through the current paths of the other of such active mechanisms, that abnormal conditioning originating in any one of such paths will cause like conditioning of the other of such paths the same as if such abnormal conditioning originated in such paths.

11. In a non-interference repeater,—individual unit mechanisms for respective re-

sponse to a plurality of normally independent current paths, in combination with means responsive to the activity of said mechanisms for effecting serial interconnection between the circuits of simultaneously active mechanisms.

12. In a non-interference repeater for fire alarm, telegraph systems of the type described, means responsive to signaling activity thereof for automatically effecting serial interconnection between originating circuits associated therewith.

In witness whereof, I hereunto subscribe my name, this 24th day of February, 1928.

FREDERICK B. PHILBRICK
